UNITED STATES PATENT OFFICE.

CORNELIUS B. CORCORAN, DECEASED, LATE OF NEW YORK, N. Y.; BY MICHAEL J. CORCORAN, ADMINISTRATOR, OF BROOKLYN, AND ALFRED G. F. KUROWSKI, OF BROOKLYN, NEW YORK, ASSIGNEES TO UNDERWOOD TYPEWRITER COMPANY, OF NEW YORK, N. Y., A CORPORATION OF DELAWARE.

TYPEWRITING MACHINE.

Original application filed December 30, 1922, Serial No. 609,793. Divided and this application filed January 12, 1926. Serial No. 80,692.

This invention relates to means for facilitating the operation of a line-spacing mechanism of a typewriting machine in a sound-deadening casing, with the line-spacing mechanism readily operable from the exterior of the casing.

In the Underwood portable typewriting machine, the line-spacing mechanism is mounted at the rear part of the machine, so that when the machine is placed in a sound-deadening casing the line-spacing mechanism is much nearer the top and rear than the front of the casing.

A feature of the present invention relates to the provision of a line-space lever extending through the top of the casing, and so mounted on the carriage that it will readily operate the line-spacing mechanism, the lever being attachable to or detachable from the carriage when the latter is used with or without a sound-deadening casing.

Another feature of the invention is the provision of a bracket attached to the carriage and upon which the line-space lever is pivoted, there being no changes necessary on the carriage for attaching the bracket and the line-space lever thereto. Means is provided on the bracket to co-operate with means on the line-space lever for limiting and steadyng the movement of the latter. The means may comprise an outwardly-extending arm on the bracket having shoulders for engagement with a pin on the line-space lever thereby determining the throw of the lever.

This application is a division of application, Serial No. 609,793, filed December 30, 1922.

Other features and advantages will hereinafter appear.

In the accompanying drawings,

Figure 1 is a cross-sectional view through the center of a sound-deadening casing and a typewriting machine therein with the invention applied thereto.

Figure 2 is a front view of the line-space mechanism, showing the line-space lever and the supporting bracket therefor.

Figure 3 is a view, in side elevation, taken on the line 3-3 of Figure 2.

Figure 4 is a detail perspective view of the bracket which supports the line-space lever.

The casing comprises a body portion 10 divided longitudinally by a plate 11, which extends from one to the other of the side walls 12 of the casing. The plate 11 is offset at its lower edge to form a flange 13, through which are passed wood screws 14, securing the plate to the base 15 of the body-part of the casing. The plate 11 may be further braced by means of a strip 16 extending longitudinally thereof on the base 15. A similar strip 17 may be extended from side to side of the body-part, at the forward edge thereof, where the cover engages the base. The plate 11, together with the rear wall 18 of the part 10, and the side walls of the latter, forms an interior chamber adapted to receive the main frame 19 and the carriage 20 of a typewriting machine. The keyboard-extension 21 of the machine protrudes through, and forward of, the plate 11, so that the keyboard may be accessible when the outer cover (not shown) is removed. This interior chamber has the rear wall thereof lined with sound-deadening material 22; the side walls thereof with sound-deadening material 23; the base thereof with sound-deadening material 24; and the front thereof with sound-deadening material 25, which latter is suitably secured to the plate 11. This interior chamber is also provided with a cover 26, adapted to be swung up from its normal position, in which position access may be had to the machine, for erasures and the like.

For centering and holding the machine to the casing base 15, the rear feet 27 of the machine are moved into brackets 28 and the front feet 29 into disks 30. The front of the machine is locked against upward movement by a plate 31, secured to the upper edge of the plate 11, and which crosses over, and fits down upon, the front plate 32 of the machine. This plate 31 is provided with a sound-deadening lining 33 and forms an upward continuation of the front wall of the interior chamber to the lower front edge of the interior cover 26 when the latter is in normal position.

The cover, like the rest of the interior casing, is provided with a lining 34; and this lining is provided with a facing-piece 35, of sheet-metal or other material, to prevent

fouling of the paper, in the machine, on the lining 34 as the carriage is moved in letter-feed and return directions.

The lower edges of the side lining-members 36 of the cover are held by strips 37.

In the front of the cover is a window, through which the writing on the platen may be observed. A window-pane of glass or other transparent material, is set into a frame provided therefor in the cover. In the drawings, the pane is shown as comprising superposed sheets of glass 38 and 39. At the lower end of the window is a cushion 40, which rests upon an offset 41 on the upper edge of the removable front plate 31, when the cover is in normal position.

Since the machine is to be operated in the sound-proof inner casing, and since the side walls 12 of the casing-part 10 form also the side walls of the interior sound-proof chamber, the length of the several parts of the casing must be such as to allow for full movement of the carriage in letter-feed and return directions on the machine. Secured to the carriage, however, are various operating levers and arms which should be accessible from the outside of the sound-proof chamber. One of these levers comprises a line-space lever 42 (and is the only one shown in the drawings). If these levers are to project to the outside of the sound-proof chamber, the latter must be slotted to permit them to travel therewith along with the carriage. Such a slot is shown at 43 in the cover at the rear of the window-pane. Resilient cushions 44 are provided which come together to close the slot, except at the points where the levers protrude therethrough.

The line-space mechanism in the Underwood standard portable typewriter consists of a ratchet-wheel 45, fast on the shaft 46 of the platen 47. A pawl 48, for actuating the ratchet-wheel, is mounted on a slide 49, connected to one arm 50 of a bell-crank-lever, pivoted at 51 on the carriage-frame. The other arm 52 of the bell-crank lever projects forward and terminates in a finger-piece 53 within the interior sound-proof chamber. This finger-piece is adapted to be engaged and operated by the lever 42, which projects through the slot 43 to the outside of the cover. The lever 42 is pivoted at 54 to an ear 55, forming part of a bracket 56. The bracket 56 has formed thereon, at the right-hand end thereof, an ear or prong 57, bent over, in the form of a hook, to engage the upper edge of the side piece 58 of the carriage-frame at the forward part of the same, and to support the bracket 56 upon the carriage-frame at this point. The bracket 56 also has a side piece or plate 59, which extends from the front of the platen, alongside the side plate 58 of the carriage, under the platen-axle, to the rear of the latter. Near the forward part of the bracket-extension 59,

substantially directly below the hook 57, a headed screw 60 is threaded into the bracket-extension 59, near the under edge of the carriage side piece 58, in such position that, when the screw is tightened, the head thereof will overlap and bear against the carriage side piece 58, thereby assisting the hook 57 in holding the bracket to the carriage. Similarly, at the rear of the bracket-extension 59, another headed screw 61 is threaded into the same, alongside the lower rear edge of the carriage side piece, and in such position that, when the screw 61 is tightened, the head thereof will overlie, and bear against, the side plate of the carriage, thereby furnishing an additional anchor for the bracket 56 at the rear of the platen. The screw 60 is turned into the bracket from the right-hand side thereof, whereas the screw 61 is turned into the bracket from the left-hand side thereof; the bracket being thus engaged from both sides of the carriage side plate. To permit the head of the screw 61 to engage the carriage side plate at the left-hand side thereof, the bracket-extension 59 is offset leftward, at 62, to bring it, at 63, to the plane of the outer or left-hand portion of the carriage side plate. The portion 63 of the bracket-extension 59 may have a further leftward lip or offset 64, the end of which is flush with the outer surface of the bracket side plate, so that the head of the screw 61, by engagement therewith, and with the outer face of the bracket side plate, may automatically and correctly position the bracket-extension 59 with respect to the carriage side plate. It will be noted from the foregoing that, although the bracket 56 is securely anchored at three points, and in different planes to the carriage side plate, there are no special attachments on the latter for the bracket, nor are there any screw-holes required in the carriage side plate for attachment of the bracket.

That reach of the bracket, to which the lever 42 is pivoted, extends lengthwise of the platen-axle, at right angles to the rearward bracket-extension 59, and thence downward with a rearward offset to the pivot-point 54 of the lever 42. The bracket 56 has another prong or extension 65, at the front thereof, lengthwise of the platen-axle. The upper edge of the bracket-extension 65 is cut away at 66, on a curve struck from the pivot-point 54; and the lever 42 carries a pin 67, adapted to travel along the curved edge of the recess 66, and to engage shoulders 68 and 69, respectively, at the right and left hand ends of the recess 66, to determine the throw of the lever 42 in either direction. To steady the lever 42 on its pivot 54, against forward and rearward angular movement, the pin 67 is provided with a head 70, to engage with the rear face of the bracket-extension 65.

The lever 42, which is operable from the exterior of the casing, is attached to the machine in such a manner that no changes have to be made to the standard parts of the machine which is advantageous since it renders the machine readily adaptable for use with or without a casing. The regular line-space arm 52, which terminates in the finger-piece 53, remains on the machine when the latter is to be operated in a sound-deadening casing. The lever 42 is so attached to the machine that when operated from the exterior of the casing its lower part will engage and operate the arm 52 in the interior of the casing in a similar manner that the operator would engage and operate the arm when the machine is used without the casing, in which case the lever 42 can easily be removed from the machine.

Variations may be resorted to within the scope of the invention, and portions of the improvements may be used without others.

Having thus described the invention, we claim:

1. In a typewriting machine, a platen, a platen-carriage having side plates beyond the ends of the platen, line-space mechanism comprising a ratchet-wheel, a pawl for engagement with the ratchet-wheel, a lever for actuating the pawl, another lever adapted to engage and operate the first lever and to protrude through a slot in a sound-deadening casing for the machine, and a bracket on which the second lever is pivoted; the bracket being attachable to the side plate of the carriage.

2. In a typewriting machine, a platen, a platen-carriage having side plates beyond the ends of the platen, line-space mechanism comprising a ratchet-wheel, a pawl for engagement with the ratchet-wheel, a lever for actuating the pawl, another lever adapted to engage and operate the first lever and to protrude through a slot in a sound-deadening casing for the machine, a bracket on which the second lever is pivoted, and means exclusively confined to the bracket for attaching the bracket to the side plate of the carriage.

3. In a typewriting machine, a platen, a platen-carriage having side plates beyond the ends of the platen, line-space mechanism comprising a ratchet-wheel, a pawl for engagement with the ratchet-wheel, a lever for actuating the pawl, another lever adapted to engage and operate the first lever and to protrude through a slot in a sound-deadening casing for the machine, a bracket on which the second lever is pivoted, means exclusively confined to the bracket for attaching the bracket to the side plate of the carriage, such attaching means consisting of an offset or hook on the bracket adapted to be hung on the carriage side plate, and a headed screw on the bracket adapted when tightened to

overlie and engage the face of the carriage side plate at the edge of the latter.

4. In a typewriting machine, a platen, a platen-carriage having side plates beyond the ends of the platen, line-space mechanism comprising a ratchet-wheel, a pawl for engagement with the ratchet-wheel, a lever for actuating the pawl, another lever adapted to engage and operate the first lever and to protrude through a slot in a sound-deadening casing for the machine, a bracket on which the second lever is pivoted, means exclusively confined to the bracket for attaching the bracket to the side plate of the carriage, such attaching means consisting of an offset or hook on the bracket adapted to be hung on the carriage side plate, and headed screws adapted to overlie and when tightened to engage the face of the carriage side plate, respectively at the front and rear edges thereof.

5. In a typewriting machine, a platen, a platen-carriage having side plates beyond the ends of the platen, line-space mechanism comprising a ratchet-wheel, a pawl for engagement with the ratchet-wheel, a lever for actuating the pawl, another lever adapted to engage and operate the first lever and to protrude through a slot in a sound-deadening casing for the machine, a bracket on which the second lever is pivoted, means exclusively confined to the bracket for attaching the bracket to the side plate of the carriage, such attaching means consisting of an offset or hook on the bracket adapted to be hung on the carriage side plate, and headed screws adapted to overlie and when tightened to engage the face of the carriage side plate, respectively at the front and rear edges thereof, one of the screws engaging the carriage side plate on the right-hand side thereof and the other of the screws engaging the carriage side plate on the left-hand side thereof.

6. In a typewriting machine, a platen, a platen-carriage having side plates beyond the ends of the platen, line-space mechanism comprising a ratchet-wheel, a pawl for engagement with the ratchet-wheel, a lever for actuating the pawl, another lever adapted to engage and operate the first lever and to protrude vertically upward through a slot in the top of a sound-proof casing for the machine, and a bracket on which the second lever is pivoted; the bracket being attachable to the side plate of the carriage.

7. In a typewriting machine, a platen, a platen-carriage having side plates beyond the ends of the platen, line-space mechanism comprising a ratchet-wheel, a pawl for engagement with the ratchet-wheel, a lever for actuating the pawl, another lever adapted to engage and operate the first lever and to protrude vertically upward through a slot in the top of a sound-proof casing for the ma-

chine, and a bracket on which the second lever is pivoted; the bracket being attachable to the side plate of the carriage and having a portion parallel to the axis of the platen, and the second lever having a headed pin thereon adapted, when the lever is actuated, to ride upon the edge of such portion of the bracket, with the bracket between the lever and the head of the pin, whereby the lever is steadied against forward and rearward angular displacement.

8. In a typewriting machine, a platen, a platen-carriage having side plates beyond the ends of the platen, line-space mechanism comprising a ratchet-wheel, a pawl for engagement with the ratchet-wheel, a lever for

actuating the pawl, another lever adapted to engage and operate the first lever and to protrude through a slot in a sound-deadening casing for the machine, and a bracket on which the second lever is pivoted; the bracket being attachable to the side plate of the carriage, and the second lever having a pin thereon adapted when the lever is actuated to ride on a portion of the bracket, and shoulders on such portion of the bracket to determine the throw of the second lever.
